FOLDING DISPLAY CARTON

Paul E. Olivier, New Orleans, La., assignor to
 Great Southern Box Company, Inc., Southport,
 La., a corporation of Louisiana

Application June 6, 1938, Serial No. 212,137

10 Claims. (Cl. 206—44)

This invention relates to cartons of the type formed by folding up the shaped and score-defined panels of a blank of any suitable and light material such as craft-board.

5 One of the objects of the invention is to provide a strong light and rigid shipping container.

Another object of the invention is the provision of a carton of the class described having a front panel which may be lowered for the display of the 10 contained commodity, and which when closed forms a positive tie between the ends of the carton.

A further object of the invention is to provide the carton having the hinged front panel which 15 ties in the ends of the carton when closed, with a lid or top having the common function when in place of keeping the front panel closed and locking the front and ends in inter-tied relation.

Still another object is to provide a carton having hollow walled parallelepipedal ends of plural 20 ply thickness with flat front faces against which the lateral margins of the front panel seat and having slots in said front faces receiving tongues on said front panel for tying the front and ends 25 together.

Another object of the invention is the provision of a carton having the parallelepipedal hollow 30 ends in which the flat top faces of said ends are extended at the rear so as to project inwardly forming reinforcing webs with tongues interlocking through slots, with the back panel, forming rigid trihedral corners at the upper rear of said carton.

A further object of the invention is a carton 35 having the hollow walled parallelepipedal ends as described with shelf slots through the inner panels, said slots opening in the flat front faces of the ends, to some depth so that shelves can be introduced into said slots from the front of the 40 carton.

Still another object of the invention is the provision of a blank, so cut, scored and perforated as, when folded and secured, to form the carton as herein illustrated and described.

45 Other objects of the invention will appear as the following description of a preferred and practical embodiment thereof proceeds.

In the drawings throughout the several figures of which the same characters of reference have 50 been used to denote identical parts:

Figure 1 is a perspective view of a closed carton embodying the principles of the present invention;

55 Figure 2 is the same carton with the top opened and the front lowered;

Figure 3 is a plan view of the blank in which the carton is constructed;

Figure 4 is a cross section through the carton;

Figure 5 is a horizontal section showing in detail the front and rear corner construction in the closed carton; and

Figure 6 is a perspective view illustrating the construction which forms the rigid trihedral rear corner.

10 Referring now in detail to the several figures and first referring to Figures 1 and 2 in which the carton is shown in assembled form, it comprises a bottom panel 1, back panel 2, flanged top or lid 3 and hinged front panel 4. These as shown are all folded from an integral blank and include also the ends 5 and 6 which are of hollow construction and parallelepipedal in shape providing the flat front walls 7 and 8 and the flat top walls 9 and 10. The top walls at the rear 20 are expanded inwardly forming reinforcing webs 11 and 12 terminating in tongues 13 and 14 (for tongue 14, see Figure 6) which tongues protrude through slots 15 and 16 formed immediately below the line of fold between the back panel 2 25 and the lid 3. Figure 6 shows that the tongues are bent down against the outside rear of the back panel 2 and suitably secured thereto. The securing means here shown are staples 17, but other equivalent means such as pasting or stitching may be employed.

The top or lid 3 has a front flange 17' of double construction and side flanges 44 extended at their forward ends to form tongues 45, see Figure 3. Said tongues are folded angularly into the plane 35 of the front flange and inserted between the folds of said front flange. The two plies of the front flanges and tongues 45 are suitably secured together as by the staples 19. The front edge 20 of the front panel 4 is folded double and secured in a similar manner. At opposite sides of the front edge 20 are the tongues 21 which are angularly folded and when the front panel is in raised or closed position, the tongues 21 slide into slots 22 and 23 formed in the flat front 40 faces 7 and 8 of the ends of the carton. Trihedral corners at the upper rear of the carton formed by the juncture of the back panel 2, the ends of the carton and webs 11 and 12 maintain the ends of the carton in rigid perpendicular relation both to the back and bottom of the carton. The front portions of the ends are prevented from spreading through pressure of the contents or from other causes by the interlocking relation of the front to the ends provided by the 55

tongues 21 when they are interdigitated with respect to the slots 22 and 23.

The inner walls 24 and 25 of the ends of the carton are provided with the transverse slots 26 and 27 which extend depthwise into the front faces of the ends as at 28 and 29 so that shelves can be slidably introduced into said slots from the front of the carton when the front panel 4 is in lowered or opened position as shown in Figure 2. When the front panel is closed its lateral margins seat against the flat front faces 7 and 8 of the ends 5 and 6 and when the top or lid 3 is swung down to closed position, the front flange 17' overlaps the edge 20 of the front panel 17 forming the dual function of holding the front panel closed and maintaining the tongues 21 in the slots 22 and 23.

The details of construction of the hollow ends of the carton may be understood from a consideration of the blank shown in Figure 3 in which it will be seen that the bottom panel 1 is provided with the end panels 30 and 31 which fold up on the score lines 32 and 33, that the back panel 2 is provided with the end panels 34 and 35 which fold forwardly along the score lines 36 and 37 after the back has been folded to its upright position and that the end panels 30 and 31 are provided with the inner wall panels 24 and 25 which fold inwardly along the score lines 40 and 41 after the end panels have been raised to their normal upright position, the inner wall panels folding inwardly again upon the score lines 42 and 43 when the end panels 30 and 31 are in their upright position forming the flat front faces 7 and 8 hitherto described. The free inner edges of the inner wall panels 24 and 25 are folded along the score lines 62 and 63 to form the flaps 64 and 65 which bear against the back wall panel 2 and being suitably secured thereto as by staples.

The end panels 30 and 31 are provided at their upper ends with extensions 46 and 47 slotted obliquely as at 48 and 49 to define the webs 11 and 12 and folded upon the score lines 50 and 51 which define the upper edges of the end panels and foldable once again upon the score lines 52 and 53 to define the upper flat faces 9 and 10 and the flaps 56 and 57, the latter turning down inside of the parallelepipedal ends and lying in contact with the inner wall panels 24 and 25. Said inner wall panels are formed with the shallow indents 58 and 59 in which the bases of the webs 11 and 12 seat in the folded carton so that said webs lie flush with the plane of the tops of the ends of the container.

The rectangular apertures 60, only one of which is shown in Figure 2 are mere incidents of the blank construction, being the spaces originally occupied by the tongues 21.

For purposes of ventilation, the front and back of the carton may be provided with the apertures 61. If for any reason it may be desired to exclude light from the closed carton, the apertures 61, also the shelves and shelf slots 26 may be omitted.

It will be understood from the above description that I have provided a display container which may have the front panel let down hinged along its base line 66 to display the contents of the container which may be resting upon insertable shelves, that the container is of thoroughly rigid right angular construction not only by virtue of the trihedral corners at the upper rear, but also when closed by the tieing in of the forward portions of the ends by the tongues 21

and by the enveloping action of the lid 3 which closes down over the front holding it in closed position and incidentally holding the shelves against removal. It will also be understood by those skilled in the art that the invention includes not only the specific embodiment as illustrated and described, but extends to such modifications in construction and arrangement of the various panels and other parts as may be within the terms of the appended claims.

What I claim is:

1. Container of the type formed by folding a blank of sheet material along predetermined lines of fold, comprising a bottom and a back panel, hollow parallelepipedal ends fixedly related to said bottom and back panels having flat front faces of appreciable width, a front panel hingedly related at its lower edge to said bottom panel having its lateral margins resting against the flat front faces of said ends when said front panel is closed, and a flanged lid hingedly related at its rear to the upper edge of said back panel having its front flange overlapping said front panel when said front and top panels are closed.

2. Container of the type formed by folding a blank of sheet material along predetermined lines of fold, comprising a bottom and a back panel, hollow parallelepipedal ends fixedly related to said bottom and back panels having flat front faces of appreciable width, a front panel hingedly related at its lower edge to said bottom panel having its lateral margins resting against the flat front faces of said ends when said front panel is closed, said front panel being formed with tongues at its opposite sides fitting into slots in the flat front faces of said ends, a flanged lid hingedly related at its rear to the upper edge of said back panel, having its front flange overlapping said front panel when said front panel and lid are closed.

3. Container of the type formed by folding a blank of sheet material, comprising a bottom and back panel, hollow parallelepipedal ends fixedly related to said bottom and back panels having flat front faces of appreciable width, a front panel hingedly related at its lower edge to said bottom panel having its lateral margins resting against the flat front faces of said ends when said front panel is closed, said front panel being provided with tongues at its opposite sides fitting into slots in the flat front faces of said ends, a lid hingedly joined at its rear to the upper edge of said back panel, said lid having a front flange overlapping said front panel when said front panel and lid are in closed position.

4. Container of the type formed by folding a blank of sheet material along predetermined lines of fold, comprising a bottom and a back panel, hollow parallelepipedal ends fixedly related to said bottom and back panels having flat top faces of appreciable width, expanded at the rear into webs, inwardly overlying said ends, said webs having rear edges in the plane of the pack panel, and tongues extending from said edges through slots in said back panel, said tongues being secured to said back panel.

5. Container of the type formed by folding a blank of sheet material along predetermined lines of fold, comprising a bottom and back panel, hollow parallelepipedal ends fixedly related to said bottom and back panels having flat front faces of appreciable width, webs integral with said ends and fixed relative to said back panel forming with said ends and back panel rigid trihedral corners at the top rear of said container, a front panel

hingedly related at its lower edge to said bottom panel, having its lateral margins resting against the flat front faces of said ends, and a flanged lid hingedly related at its rear to the upper edge of said back panel, overlying said webs and having its front flange overlapping said front panel when said panel and lid are in closed position.

5 6. Container as claimed in claim 5, said front panel having tongues entering slots formed in the 10 flat front faces of said ends.

7. Container of the type formed by folding a blank of sheet material along predetermined lines of fold, comprising a bottom and a back panel, hollow parallelepipedal ends fixedly related to 15 said bottom and back panels having outer and inner walls and flat top faces of appreciable width, said top faces being expanded at the rear into webs inwardly overlying said ends, having rear edges in the plane of the back panel and 20 tongues extending from said edges through slots in said back panel and being secured to said back panel, said top faces being formed with downwardly turned flap extensions coinciding with the inner surfaces of said inner walls.

25 8. Container of the type formed by folding a blank of sheet material along predetermined lines of fold, comprising a bottom and a back panel, hollow parallelepipedal ends fixedly related to said bottom and back panels having inner and outer walls and flat front faces of appreciable width, said inner walls being provided with trans-

verse shelf slots extending depthwise into said flat front faces.

9. Container as claimed in claim 8, including a front panel hingedly relates at its lower edge to said bottom panel, having its lateral margins resting against the flat front faces of said ends, when said front panel is closed, occluding the ends of said shelf slots, and a flanged lid hingedly related at its rear to the upper edge of said back panel having its front flange overlapping said front panel for holding it in closed position.

10. Container of the type formed by folding a blank of sheet material along predetermined lines of fold comprising a bottom and back panel and hollow parallelepipedal ends fixedly related to 15 said bottom and back panels having inner and outer walls and flat front and top faces of appreciable width, said top faces being expanded at the rear into webs inwardly overhanging said ends having rear edges in the plane of the back 20 panel and tongues extending from said edges through slots in said back panel, said tongues being secured through said back panel, said inner walls being cut out in those portions intersected by said web whereby the upper surfaces of said 25 ends including said webs lie in the plane of the upper edge of said back panel, and a flanged lid hingedly related to the upper edge of said back panel adapted when closed to rest upon the top faces of said ends including said webs.

PAUL E. OLIVIER.
